UNITED STATES PATENT OFFICE.

EDWARD EGG, OF SCANDIA, KANSAS.

DEVICE FOR HOLDING TOPS OF BOXES OPEN.

SPECIFICATION forming part of Letters Patent No. 664,935, dated January 1, 1901.

Application filed April 30, 1900. Serial No. 14,889. (No model.)

To all whom it may concern:

Be it known that I, EDWARD EGG, a citizen of the United States, residing at Scandia, in the county of Republic and State of Kansas, have invented certain new and useful Improvements in Devices for Holding the Tops of Boxes Open; and I do hereby declare the following to be a full, clear, and exact description of the invention, such as will enable others skilled in the art to which it appertains to make and use the same.

This invention has relation to means for holding box-covers open at any required angle, being specially designed for display purposes and obviating the necessity of piling boxes in the rear of the one exhibiting the goods placed for public observation.

The device is particularly designed for cigar-boxes and is separate and independent thereof, so as to be used repeatedly with different boxes, and is of such formation as to admit of its being cheaply and easily manufactured and placed upon the market at a nominal cost.

The invention consists of the novel features, details of construction, and combination of the parts, which hereinafter will be more fully disclosed and finally claimed, and for this purpose and also to acquire a knowledge of the merits of the invention and the structural details of the means whereby the results are attained reference is to be had to the appended description and the drawings hereto attached.

While the essential and characteristic features of the invention are necessarily susceptible of modification, still the preferred embodiment of the invention is illustrated in the accompanying drawings, in which—

Figure 1 is a perspective view of a box, showing the application of the invention. Fig. 2 is a side elevation showing a portion of the box. Fig. 3 is a detail view in perspective of the parts shown in Fig. 2. Fig. 4 is a detail perspective view of the device *per se*.

Corresponding and like parts are referred to in the following description and indicated in all the views of the drawings by the same reference characters.

The device in its simplest form comprises terminal clips 1 and 2, having a right-angular disposition—that is, the clip 2 is arranged

relatively at a right angle to the plane of the clip 1. Both clips involve a spring construction, so as to automatically clamp the sides of the parts fitted thereto. This construction is necessary in order to prevent possible slipping and enable the clips to adapt themselves to slight variations in the thickness of material comprising the parts of the box or package to which they are respectively fitted. The body 3 of the device is about in the plane of the clip 1 and is curved throughout its length.

The article is formed of a single length of wire of proper gage, according to the size of the box for which the device is designed, and this wire is resilient, so as to retain the shape imparted thereto and provide the spring action necessary for the successful operation of the clips 1 and 2. The wire is bent at a point between its ends into approximately C form, and its end portions are rebent to provide the clips 1 and 2. The clip 1 curves longitudinally in conformity to the circular outline of the body portion of the holder. A fold 4 connects the clip 2 with the body 3 and is necessary to throw the said clip 2 wholly to one side of the plane of the body. The clips 1 and 2 project laterally from the same side of the body, thereby leaving the outer side of the article flat or free of projecting parts which would extend beyond the end of the box when fitted thereto and which would prevent the close assembling of a series of boxes. The clips may project from one side or the other from the plane of the body, according as the holder is intended for use at the right-hand or the left-hand end of a box. In other words, the device or holder will be constructed in rights and lefts.

In practice the clip 1 is engaged over the end piece 5 of a box 6, adjacent to the hinge of the cover 7, and the clip 2 is fitted to the end of the said cover 7 in proximal relation to the hinge, the parts 5 and 7 being clamped between the members of the respective clips with sufficient force to hold the cover open at the required inclination.

The device being constructed of wire can be cheaply manufactured in quantity by machinery and is effective in use and provides means for holding the hinged cover of a box open at any required angle and is especially

adapted when it is required to display goods in the package without removing them from the box or receptacle.

The clip 1 curving longitudinally obtains sufficient engagement with the sides of the edge portion of the part 5 to prevent slipping without extending down too far along the inner side of the part 5 and disturbing the goods. Moreover, either clip 1 or 2 can be shifted to hold the cover 7 open at the desired angle. The fold 4, in addition to forming an element of the clip 2, is adapted to hold a ticket, slip, or like article containing any matter to be prominently displayed.

15 Having thus described the invention, what is claimed as new is—

1. A holder for box-covers, provided at one end with a clip and at its opposite end with a clip and a fold, the latter constituting an element of the proximal clip and adapted to hold a ticket, substantially as described.

2. A holder for box-covers, provided at one end with a longitudinally-curved clip, and at

its opposite end with a laterally-extending clip and fold having an element common to each said fold being adapted to hold a ticket, substantially as described.

3. As an improved article of manufacture, a device for holding open hinged box-covers, the same consisting of a single length of wire 30 bent intermediate of its ends into approximately C form and having one of its terminal portions bent to provide a clip at one side of the body and in a plane parallel therewith, said clip curving longitudinally in conformity to the adjacent portion of the body, and the opposite end portion of the wire being bent laterally to provide a fold and a clip at one side of the body and in a plane at a right angle thereto, substantially as described. 35

In testimony whereof I affix my signature in presence of two witnesses.

EDWARD EGG. [L. S.]
